BUTTON LOOP

Application filed June 28, 1929. Serial No. 374,395.

This invention relates to button loops having multiple means to connect a single strap with spaced buttons carried by a garment intended to be supported by the strap.

5 The object of the invention is to provide a double button loop with laterally yieldable restricted entrances to the retaining loops, a side portion of each entrance yieldingly cooperating with a side portion of the other entrance.

10 The invention consists in the novel constructions, to be hereinafter described or claimed, for carrying out the above stated object and such other objects as may herein-
15 after appear.

15 The character of the invention may be best understood by reference to one illustrative device embodying the invention and illustrated by the figures in the accompanying drawing of which the Figure 1 is an elevation of a double button loop illustrated in normal condition; and the Figure 2 is a similar elevation but illustrating the double loop in expanded condition.

20 The device, as illustrated, is a double button loop for connecting suspender strap to two buttons properly spaced apart and provided by a garment, or the like, and comprises the two button receiving loops 1 and 2 and the two button retaining loops 3 and 4, each of the receiving loops being associated in axial alignment with a retaining loop having an expansible restricted entrance. The double button loop is preferably formed of a 25 single piece of resilient wire of which a middle portion is bent to form the separating loop 5 either side of which provides an inner side arm 6 of a button loop, and the remaining end portions 14 and 15 of the wire are overlapped in cross relation and bent to form the retaining loops 3 and 4 and the outer side arms 7 of the button loops 1 and 2, the wire extremities being provided with the eyes 8 adapted for a sliding pivotal connection with 30 the bar portions 9 of a suspension loop, slide buckle, or the like. Each button loop 1 and 2 is provided with a yieldable restricted opening 10 through which communication is had between each of the axially aligned loops 1 and 3, and 2 and 4, respectively. A portion

of the overlapped wire is enclosed within the ferrule covering 11 to permit a relative longitudinal movement of the enclosed overlapped wire without the possibility of bodily separation.

55 As the spaced buttons having the shanks 12 and 13, illustrated in cross section by the Figure 1, are received within the loops 1 and 2, respectively, a downwardly directed force applied to these shanks will cause each to act as a cam to operate and expand a restricted opening, as illustrated by the Figure 2, to permit the passing of each shank into a retaining loop. As this expansion takes place, the oscillating movements of the outer side arms 7, which in ordinary constructions of double loops must bear the entire movement of expansion if any, is thereby minimized; for the base of each button loop is permitted to bodily move laterally outward as the cam action places a lateral stress upon the outer side arms 7. The resiliency of the double button loop permitting these bodily movements of the two base portions is obtained from the extended wire connection of each 60 base portion with the farthest inner side arm 6 which is drawn, together with the connected side arm 7, to a laterally moved position that cooperates with the bodily movement of the base of the other button loop to 65 expand the normally restricted openings in both button loops to make easy the simultaneous passage of both button shanks from one loop to the other of their respective button loops. The extremities illustrated as 70 terminating in the eyes 8, if desired, may be made to abut and secured together by welding or in any other manner; for the invention is not limited to any specific form of construction and the details of the device as illustrated 75 and explained may be varied to produce the novel features herein claimed and to advantageously combine such a double button loop in connection with other elements adapted to be employed in garment supporters.

I claim:

1. A double button loop having associated button loops relatively spaced by means of a separating loop, the double loop comprising a resilient wire a middle portion of which is

bent to form the separating loop of which the outer sides provide the inner sides of the associated loops, the wire extremities being returned inwardly and overlapped and each further bent to form the base and outer side of the opposite button loop.

2. A double button loop having associated button loops relatively spaced by means of a separating loop, the double loop comprising

10 a resilient wire a middle portion of which is bent to form the separating loop of which the outer sides provide the inner sides of the associated loops, the wire extremities being returned inwardly and overlapped and each further bent to form the base and outer side of the opposite button loop, portions of the overlapped wires being secured together to permit only a relative movement in the plane of the button loop.

15 3. A double button loop having associated button loops relatively spaced by means of a separating loop, the double loop comprising a single piece of resilient wire the middle portion of which is bent to form a separating loop of which the outer sides provide the inner sides of the associated loops including an intermediate shoulder, the wire extremities being returned inwardly and overlapped and each further bent to form the base and outer side of the oppositely positioned associated button loop including an intermediate shoulder opposing the other shoulder to provide the associated button loops with normally contracted throats co-operatingly

35 yieldable.

JESSUP SALISBURY.
